UNITED STATES PATENT OFFICE.

RICHARD D. GALLAGHER, JR., OF FLATBUSH, NEW YORK, ASSIGNOR TO STANDARD COUPLER COMPANY, OF NEW YORK, N. Y., A CORPORATION OF NEW JERSEY.

YIELDING RESISTANCE UNIT FOR CAR BUFFERS.

1,423,522.

Specification of Letters Patent. Patented July 23, 1922.

Application filed July 8, 1921. Serial No. 423,349.

To all whom it may concern:

Be it known that I, RICHARD D. GALLAGHER, Jr., a citizen of the United States, residing at Flatbush, in the county of Kings 5 and State of New York, have invented certain new and useful Improvements in Yielding Resistance Units for Car Buffers; and I do hereby declare the following to be a full, clear, and exact description of the 10 same, reference being had to the accompanying drawings, forming part of this specification.

The objects of the present invention are to provide a self-contained yielding resistance 15 unit which is particularly adapted for use in connection with car buffers, and in the embodiment of the invention adapted for this particular use and adopted for illustrative purposes, the device is designed to be 20 placed back of the center stem of the buffer and to impose yielding resistance to the inward movement of that stem. This yielding resistance is made most effective in the design of the present device by providing 25 for an inward movement of the buffer for a certain distance against minimum resistance sufficient to keep the buffers together and to impose some retardation on the movement of the cars toward each other, 30 but which resistance is augmented very much during the intermediate portion of the inward movement of the buffer with a final yielding resistance just before the limit of movement is reached, which will be sufficient 35 to practically cushion the entire load which can be sustained by the working parts of the buffer mechanism.

In accomplishing the objects aimed at, the resilient and movable parts of the resistance unit are mounted in a housing 40 which may be conveniently termed a barrel, although it is more or less rectangular in cross section and made to fit the space between the frame members of the car, and the 45 said movable and yielding members are so arranged and formed as that when the yielding resistance of the initial movement has reached its desired limit, the secondary and heavier resistance elements will be 50 brought into play and when they have reached the desired limit the final resistance element will be brought into play and at the limit of this movement a solid connection or bearing is afforded which will have 55 a strength for resistance purposes equal to

the strength of the stem of the buffer and other supporting parts of the car, without setting or destroying the recovery of the spring or yielding members themselves.

Referring to the accompanying drawings, 60

Figures 1, 2 and 3 are a plan, a side and an end elevation, respectively, of the part which I will herein term the barrel of the 65 resistance unit.

Fig. 4 is a top plan view of the working parts of the unit with the barrel and retaining caps in section.

Fig. 5 is a section on the line 5—5 of 70 Fig. 4.

Figs. 6, 7 and 8 are a plan, and a side and an end elevation, respectively, of the intermediate follower of the series of followers.

Fig. 9 is a front elevation of the third 75 follower.

Fig. 10 is a horizontal section through the same with the final or spring abutment follower in position therein.

The housing or barrel shown separately in Figs. 1, 2 and 3 may be conveniently 80 formed of a malleable casting of proper dimensions transversely and longitudinally to fit in the available space in the car framing immediately behind and in line with the center stem of the buffer. It is conveniently of rectangular form in cross section with the forward end entirely open and the top and bottom walls cut back from the front end in the form of recesses indicated at A in the drawings. The walls of the barrel are strengthened, and suitable longitudinal bearing surfaces formed by thickened portions indicated at B, B', B², B³, on the exterior for co-operation with the supporting and enclosing portions of the car 95 framing, and at C on the interior, as shown, for example, in Fig. 3, for co-operation with the movable members or followers within the barrel.

Cap pieces D which may be conveniently 100 struck up from sheet metal are adapted to fit in the mouth of the barrel on opposite sides and to be retained in position by heavy rivets d passing through the sides of the 105 barrel and cap pieces, the outer heads of the rivets being located in recesses so as to avoid external projection. These cap pieces D partly close the mouth of the barrel but leave between their adjacent front edges a 110 space or opening, preferably rectangular

and of a proper size to permit of the entry of the center stem of the buffer during the period when the buffer is in action and they further function as the retaining means whereby all of the operating parts of the resistance unit are held within the barrel so as to constitute a self-contained unit which may be manufactured and shipped ready for installation.

10 In the general scheme of the preferred arrangement of the yielding members of the resistance unit, three sets of springs are employed. One set of springs is relatively long and comparatively light and acts first to 15 take up lost motion between the buffers of adjacent cars and offers only a reasonable resistance to the inward movement of the buffer. The second set is also made up of coiled springs, but of much higher resistance than the first set and has a less range 20 of movement, while the final set is preferably made up of spring plates which will have a very high resistance capacity and a relatively short range of movement, coupled with a considerable additional resistance due to the friction between the plates, thus transferring the yielding movement to the solid bearing against the car frame with a minimum blow or shock under extreme 25 conditions.

The first set of springs above referred to are indicated by reference letter E, and they are preferably arranged concentrically at the center of the forward end of the barrel, 30 in which position they are retained by seating in a suitable recess or seat in a front follower H and in an intermediate follower I. This intermediate follower also has seats in its rear face for the forward ends 35 of the second set of coil springs F. There are preferably twin sets of coil springs F arranged side-by-side. The rear ends of the springs F are seated and guided in openings in the third follower K, and they seat 40 against what might be termed the supplemental or final follower L. Both the followers K and L bear against the forward face of the first plate of a series of curved 45 spring plates M which occupy the bottom 50 of the barrel and between which and the bottom wall of the barrel there is interposed a wear plate N, which latter also serves to distribute the strains over the bottom wall 55 of the barrel and assists in preventing any possible rupture of the latter.

Each of the followers is formed to be guided in its back and forth movements by the interior conformation of the barrel so as to prevent lateral displacement sufficient 60 in extent to get the springs or other parts out of alignment and in addition the edges of the walls of adjacent followers are preferably adapted to contact at the moment when the limit of relative movement is 65 reached and to thereafter transmit the buff-

ing strains without imposing further compression on the spring members. With this object in view, it will be noted that the normal distance between follower H and follower I is considerably greater than the distance between the follower I and follower K, and the spring E has a correspondingly greater range of movement to take up slack which may exist between the cars, without imposing too high a buffering resistance.

The follower H is conveniently formed in section as shown in Fig. 5, wherein it will be noted that, while it conforms generally to the internal outline of the space in the barrel between the cap plates, it is irregular to the extent that it is provided with end recesses h to avoid any contact or engagement with the heads of the bolts or rivets d and with side, outwardly-bowed portions h' extending out into the spaces between the longitudinal edges of the cap members and ends of the barrel. The object of the latter construction is to permit of the use of springs of greater diameter than would be permitted by the thickness of the barrel, without sacrificing the strength of the parts. In other words, the available space for the reception of a device of this kind is limited and the spring referred to should be made of a diameter which leaves 95 but a small margin or space for the location of the walls of the enclosing members. By cutting back the sides of the barrel and using cap pieces as described with a space between their adjacent edges, it thus becomes possible 100 to employ larger springs than would otherwise be the case, and the device is thus adapted for the use of standard springs, if so desired.

The second or intermediate follower I in 105 which the rear end of the spring set E and the forward end of the spring set F are adapted to seat, has its forward end extended between the rear ends of the cap members D, so as to be, in part, guided thereby, and its 110 outward movement may be limited by the contact of shoulders i with the rear ends of the cap pieces D, although, ordinarily, the normal position is such that the shoulders will be in rear of the edges of said cap piece. 115 This forward end of the intermediate follower I, it will be noted from Fig. 8, is also swelled out or enlarged centrally in the recesses or cut away portions A of the barrel, so as to permit of the formation of a spring 120 seat or chamber of large diameter, and the said recess A is extended back a sufficient distance to prevent any strains being imposed on the walls of the barrel through contact therewith of the said projections or 125 swelled out portions of the follower, when driven back under the impact of the buffering strain. At its rear edge, the follower I separated from the follower K a distance which substantially conforms to the desired limit 130.

of elastic or yielding movement to be absorbed by the spring sets F, but the follower K only indirectly takes up any pressure from the springs F, inasmuch as there is 5 interposed at the rear ends of said springs the fourth or supplemental follower L. This follower L is of arch-like formation, passing around and over a cross piece k of the follower K, the projecting ends of the arch 10 or legs of the follower being adapted to seat on the spring plates M and at the same time the center of the cross piece k of the follower K seats against the center of said spring plates. With this construction, while 15 the spring sets F are guided by the follower K they seat directly against the front face of the follower L, and through the latter the pressure is transmitted both directly to the spring plates near their end and in 20 directly to the plates at the center through the cross piece k of the follower K.

In operation, owing to this arrangement of the parts, it will be seen that there is practically no yielding movement of the 25 spring plates until the limit of elasticity of the springs F is approached or reached, when, as the two followers L and K meet, the pressure will be transmitted through them to the center of the spring plates and 30 the movement or yielding action of the plates will be inaugurated, but the yielding resistance of these parts is so great, due to the strength of the springs and the friction which is maintained between them, by reason 35 of the yielding pressure at the ends of the follower L, that almost any capacity may be provided for without permitting the parts to come up solid. They will only reach the limit of elastic movement when the plates 40 M have straightened out against the wear plate N.

In assembling the parts it will be readily understood that they are to be placed in position successively before the cap pieces 45 are placed in position and that the latter are to be secured by bolting or riveting after the springs and followers are all in place. When secured in place and the end follower H allowed to return to its seat the center 50 stem receiving face of the follower is preferably arranged to project about the thickness of the walls of the cap pieces, so that the whole structure presents a neat and uniform appearance and may be readily handled as a single unit, either to be placed in 55 new car construction or substituted for equipment now installed to increase the efficiency of the service.

What I claim is:

60 1. A self-contained resilient unit for car buffers, comprising a barrel open at one end, a series of followers movable longitudinally in the barrel and adapted to contact with each other, spring members normally holding 65 the followers separated and of different yielding capacity whereby the followers will contact with each other successively, a dominant spring member for yieldingly resisting the movement of the followers as a unit when brought together, and means connected 70 with the barrel for partially closing the open end of the barrel and preventing the escape of the followers from the barrel, the face of one of said followers being exposed through the partially closed end of the 75 barrel.

2. A self-contained resilient unit for car buffers, comprising a barrel open at one end, a series of followers movable longitudinally in the barrel and adapted to contact with 80 each other, spring members normally holding the followers separated, a dominant spring member for yieldingly resisting the movement of the followers as a unit when brought together, and a supplemental follower supported by the dominant spring member and forming an abutment for resisting the pressure of the follower separating springs and means for partially closing the open end of the barrel and preventing escape 85 of the followers from the barrel, a face of one of said followers being exposed through the partially open end of said barrel.

3. A self-contained resilient unit for use on railway cars embodying a barrel open 95 at one end, a series of curved plate springs, a follower resting against the center of said springs for deflecting the same when pressure is applied to said follower, a second follower resting against said springs in 100 proximity to their ends, pressure resisting springs resting against said last mentioned follower, and means for transmitting pressure to said last mentioned springs and to said first mentioned follower and means for 105 partially closing the open end of the barrel and preventing escape of the followers from the barrel, a face of one of said followers being exposed through the partially open end of said barrel.

4. A self-contained resilient unit for use in railway cars, comprising a barrel open at one end, movable pressure absorbing members within said barrel arranged to act successively therein and comprising a dominant 115 spring set formed of curved spring plates, two separately movable followers cooperating with said dominant spring member, coil springs resting against one of said followers, a third follower for transmitting pressure to said coil springs, said third follower having a wall seating against the other follower bearing against the plate springs, whereby pressure will be transmitted to the plate 120 springs directly through the contacting followers and indirectly through the coil springs and follower against which they abut and means for partially closing the open end of the barrel and preventing escape 125 of the followers from the barrel, a face of 130

one of said followers being exposed through the partially open end of said barrel.

5. A self-contained resilient unit for car buffers comprising a barrel having recesses formed in its opposite walls and extending inwardly from the open end, followers mounted in said barrel and having transverse enlargements extending into said recesses, spring seats in said followers extending into said enlargements and springs mounted in said seats whereby springs of increased diameter may be located in said barrel and recesses.

6. In a yielding resistance unit for railway cars, the combination with a barrel open at one end and having oppositely disposed recesses in its walls extending inwardly from said open end, followers mounted in said barrel and having spring seat enlargements extending into said recesses, a spring set mounted in said seats between the followers and cap members mounted in the barrel and embracing opposite ends of the followers.

7. In a self-contained resilient unit for railway cars, the combination with a barrel having an open end and recesses in its wall extending inwardly from said open end and cap pieces mounted in said barrel and partly

closing its opening, of followers movably mounted in the barrel and having transverse 30 spring seat enlargements extending into the recesses and between the proximate edges of the cap pieces, a coil spring set mounted in said seats and of a diameter approximately the same as the internal minor diameter of the barrel, and yielding pressure 35 resisting members located within the barrel beyond said recesses with which the said followers and springs co-operate in resisting compressive strains.

8. In a yielding pressure resisting unit for railway cars, the combination of a barrel having an open end with recesses in its oppositely located walls extending inwardly from said open end, a front follower mounted in proximity to the open end of the barrel and having transverse spring seat enlargements extending into said recesses, an intermediate follower having a front spring seat enlargement extending into said recesses and rear plural spring seats within the unrecessed portion of the barrel, plural springs mounted in said last mentioned seats, and a single spring set mounted in the enlarged seats in both said followers.

RICHARD D. GALLAGHER, JR.
